ASH TRAY

Vinton D. Carrick and Nels B. Swanson, Bucyrus, Ohio

Application January 13, 1955, Serial No. 481,572

1 Claim. (Cl. 220—35)

This invention relates to receptacles, and more specifically, the invention pertains to ash trays.

One of the primary objects of this invention is to provide a smoker's ash tray with means pivotally closing the open end thereof.

Another object of this invention is to provide a smoker's ash receiving receptacle having an open upper end, a closure member for the open end pivotally connected therewith, resilient means constantly biasing the closure member for pivotal movement, and means releasably securing the closure member in its closed position.

A still further object of this invention is to provide, in an ash receiving receptacle as described above, a removable insert for directly receiving the ashes, cigarette and cigar stubs, and other expended smoker's debris whereby the tray may be maintained in a sanitary manner.

This invention contemplates, as a still further object, to provide an ash tray of the type referred to above, wherein the tray has an ornamental design simulating a turtle.

Other and further objects of this invention will become more apparent from a consideration of the following specification when read in conjunction with the annexed drawing, in which:

Figure 1 is a top plan view of an ash tray constructed according to this invention.

Figure 2 is a medial longitudinal cross-sectional view taken on the horizontal plane of line 2—2 of Figure 1, looking in the direction of the arrows.

Figure 3 is a transverse cross-sectional view taken on the vertical plane of line 3—3 of Figure 2, looking in the direction of the arrows.

Figure 4 is an enlarged detail transverse cross-sectional view taken on the line 4—4 of Figure 2.

Referring now more specifically to the drawing, reference numeral 10 designates, in general, an ash tray constructed in accordance with the teachings of this invention. As illustrated therein, the ash tray 10 is seen to comprise a receptacle having the configuration of a turtle wherein reference numeral 12 indicates the lower substantially rectangular body portion thereof which includes a pair of oppositely disposed longitudinally extending side walls 14, 16, a pair of oppositely disposed end walls 18, 20, and a bottom wall 22, the walls 14, 16, 18 and 20 all being integrally formed.

The body portion 12 is supported in elevated position over a suitable platform (not shown) by a pair of front and back legs, 24, 26 and 28, 30, respectively, the upper ends of which are integrally connected therewith at the junctures of the side walls 14, 16 with the end walls 18, 20.

The body portion 12 is provided with an integrally formed neck member 32 which projects forwardly from the end wall 18 and has an inverted substantially U-shaped configuration comprising a pair of laterally spaced side walls 34, 36 connected by a bight member 38.

A head element 40 also having an inverted, substan-

2

tially U-shaped configuration including the side walls 42, 44, and a connecting bight wall 46, is pivotally connected with the neck 32 on pin 48. As is seen in Figure 2, the head 40 has a reduced inner end 40A which is adapted to mate within the neck 32.

A pair of wire springs 50, 52 are coiled intermediate their respective ends and are mounted on the pivot pin 48, one adjacent each of the side walls 42, 44, respectively. The inner ends of the springs 50, 52 engage the exterior of the wall 18 and the other ends thereof are crossed (see Figure 4) and terminate in engagement with the underside of the bight wall 46. Thus it is seen that the head 40 is constantly biased for pivotal movement in a clockwise direction.

15 A longitudinally elongated arched closure member 54 having a substantially rectangular configuration which includes oppositely disposed side and end walls 56, 58 and 60, 62, respectively, and a top wall 64, is provided for the open upper end of the body portion 12. A rib 66 is integrally formed with a portion of the top wall 64 and end wall 62. As is seen in Figure 2, the rib 66 has a portion 66A thereof extending exteriorly of the closure member 54 which is pivotally mounted on pivot pin 68 that extends transversely across a slot 70 formed in the 20 tail element 72. The tail element 72 has the inner end thereof integrally connected with the end wall 20.

A pair of springs 74 are coiled about the pivot pin 68 on opposite sides of the tail element 72 and have one of their ends engaging within slots 76 formed in the end wall 20, and the other ends thereof engage within slots 78 formed in the end wall 62 of the closure member 54. The spring 74 bias the closure member 54 for pivotal movement in a clockwise direction as viewed in Figure 2.

The end wall 60 of the closure member 54 is provided with an integrally formed depending hook 80 which, when the closure member 54 is moved into its closed position, passes through an opening 82 formed in the bight portion 38 of the neck 32 and is engaged in releasable locking relation by the free end of the reduced inner end 40A of the head 40, the reduced end 40A serving as a keeper. Downward movement of the head 40 effects a withdrawal of the keeper from the hook whereby the closure member 54 automatically pivots to its open position.

Reference numeral 83 indicates, in general, a removable receptacle having a substantially rectangular configuration that includes the side walls 84, 86, end walls 88, 90, and a bottom wall 92. As is seen in Figures 2 and 3, the receptacle 83 is supported on the bottom wall 22 with the side and end walls thereof confronting the side and end walls of the body portion 12.

Having described and illustrated one embodiment of this invention in detail, it is to be understood that the same is offered by way of example, and that the invention is to be limited only by the scope of the appended claim.

55 What is claimed is:

An ash tray comprising a hollow body having spaced side walls, front and rear walls, a bottom wall, and an open top, a tail element integrally secured to said rear wall and extending horizontally therefrom oppositely of said front wall, said tail element having a vertical slot opening therethrough adjacent said rear wall, an inverted U-shaped neck integrally formed on said front wall and extending horizontally therefrom oppositely of said rear wall, said neck having a vertical slot opening therethrough adjacent said front wall, a head element, a reduced inverted U-shaped rear end portion on said head element, said rear end portion being positioned within said neck, means pivotally securing said rear end portion to said neck, means normally biasing said head upwardly with the engagement of said rear end portion with said neck limiting the upward movement of said head, a hol-

low closure member overlying said hollow body closing said open top, a rib depending from the medial rear portion of said closure member and extending into said slot in said tail element, a pin in said tail element extending transversely of said slot through said rib pivotally securing said closure member to said body, means engaging said body and said closure member normally biasing said closure member to open position, and a hook depending from the medial forward portion of said closure member, said hook projecting through said slot in said neck and latching with the upper rear end portion of said head to releasably secure said closure member in closed position on said body, downward movement of said head disengaging said end portion of said head from said hook to release said closure member for movement to open 15 position.
